FLUID FLOW CONTROL DEVICE

Henry Schreck, Beloit, Wis., assignor to Fairbanks, Morse & Co., Chicago, Ill., a corporation of Illinois

Application May 8, 1943, Serial No. 486,193

1 Claim. (Cl. 277—29)

1
This invention relates to fluid impulse operation of mechanism such as valves and the like, and refers in particular to an improved fluid flow control device for hydraulic actuating systems such as that disclosed in my copending application entitled "Hydraulic operation of mechanism," filed May 8, 1943, and bearing Serial No. 486,192, now being Patent No. 2,396,392, issued March 12, 1946.

An object of the invention is to provide a control valve device for operative association with a fluid flow line of a fluid pressure actuating system such as that shown in said Patent No. 2,396,392, wherein the control valve is adapted for opening the flow line in response to fluid pressure such as to permit substantially unrestricted fluid pressure delivery through the line, and for throttling return flow of fluid through the valve.

An object of the invention is to provide a relatively compact and effective control valve device for the purpose indicated, which may be readily and closely adjusted for regulating the release or return flow of fluid pressure therethrough to any desired degree.

Further objects and advantages of the present improvements will appear readily from the following description of a preferred embodiment of the device as exemplified by the accompanying drawings.

While the improved control device providing the subject of the present application, may be readily employed in fluid pressure systems generally, wherein control devices of this character are required or preferred to afford predetermined desired fluid flow characteristics, the device is particularly suited to hydraulic valve actuating systems for internal combustion engines and the like. Accordingly, it is preferred herein to describe and illustrate the device in operative association with an engine valve actuating system of hydraulic impulse type, of the form and arrangement disclosed in Patent No. 2,396,392 hereinabove mentioned, the material parts of which are incorporated herein by this reference.

In the drawing:

Fig. 1 is an assembly view, in elevation, of an engine shown in part only, incorporating a hydraulic valve actuating system including the fluid flow control device of the present invention, and

Fig. 2 is an enlarged sectional elevation of the control valve, at the head end of the pump shown in Fig. 1.

Referring first to Fig. 1 of the drawings, there are illustrated certain portions of an internal combustion engine, generally designated by the

numeral 10, including in the portion thereof shown, a cylinder assembly 11 extending above the engine crankcase (not shown). Mounted on the engine camshaft casing shown in its upper portion 22, and adjacent the cylinder 11 is an actuator pump 23 preferably of reciprocating plunger type, which is cam-actuated preferably from the engine camshaft 26 within the casing 22. The pump is supplied with operating fluid 10 from a source provided by a tank or fluid pump indicated diagrammatically at 27, through a supply header 28. A feed pipe 30 connects the source 27 to one end of the header 28, while the opposite end of header 28 is connected to source 15 27 by a return pipe 32. When the source of operating fluid is provided by a tank, as at 27, it may be somewhat elevated relative to the header 28, as shown, in order to provide a desired initial fluid-pressure head in the header. There is thus 20 provided a closed fluid system with fluid circulation therein maintained during engine operation, either by the pressure delivery function of the fluid source 27 when constituted by a fluid pump, or by the suction and fluid discharge functions of the pump 23, as will appear more fully 25 hereinafter.

Associated with the cylinder head 35 of the cylinder 11 is a valve assembly embodying a valve (not shown) which is actuated by a hydraulic 30 motor indicated generally at 40 incorporated in the valve assembly as a part thereof. Actuating fluid is delivered to the motor 40 by the pump 23, through a conduit 42 and the control valve device 43 forming the subject of the present invention and hereinafter to be described, the latter by preference being arranged at the discharge end 44 of the pump.

Turning now to the fluid pump and control valve unit 23—43 the pump thereof includes a 40 supporting frame or casing 154 having a mounting flange 155 near its lower end, for assembly 45 securement upon the upper wall of the camshaft casing 22 (Fig. 1), as by mounting studs or bolts 158. The pump plunger (not shown) within casing 154 includes a cam-follower frame 172, the latter operatively supporting a cam-follower roller 175 which engages a cam 176 of a predetermined preferably symmetrical contour not here illustrated, fixed upon the engine camshaft 26 referred to hereinbefore. A suitable compression spring not shown, is provided to urge the pump plunger and cam follower downwardly as for maintaining cam-following engagement of the roller 175 with the cam 176.

The fluid pressure delivery from the pump 23

is directed through the valve device 43 presently to be described, and through conduit 42 (Fig. 1) to the pressure chamber of the valve motor 40, and upon pressure release of the fluid delivery to the motor as effected by the pump, the fluid is returned through the pump back into the supply header 28. The principal function of the valve device 43 is to check or throttle the return flow of fluid from the valve motor, to a predetermined extent, whereby to prevent oscillatory surging of the fluid column between the pump and valve motor upon pressure release by the pump, as otherwise a hydraulic ramming or so-called hammer effect would or might be produced upon the engine valve, with attendant disruption of smooth engine operation by reason of the resulting ineffective valve-closure. By thus throttling the fluid return flow upon pump pressure release, the fluid pressure on the valve motor is relatively gradually released, which thereby allows a correspondingly gradual or attenuated closure of the engine valve in a positive and relatively quiet manner.

As shown by Fig. 2, the valve device 43 comprises a casing 214 formed to provide a fluid chamber 250 open at the casing end 251, the open end of the chamber normally being closed by a threaded head or cap element 252 sealed against fluid leakage at the opening by a suitable gasket 254. In the intermediate zone of the chamber 250, the casing is formed to provide an annular bevelled shoulder 255 constituting a valve seat for the valve head 256 of a valve element 258. As controlled by valve element 258, the seat 255 may be said to define the main valve port of the device. The valve element which is of substantially tubular form to provide a central longitudinal bore or passage 259, and is externally flanged or spidered rearwardly from the valve head 256, is movable longitudinally in chamber 250, being guided in such movement by engagement of its flanges with the casing wall portion 260 of reduced diameter near the inner end 262 of the chamber. A suitable compression spring 263 bearing at one end against the cap 252 and at its opposite end against a seat 264 on the valve head 256, serves to bias the valve element inwardly of the chamber 250 to seat the valve head on the chamber seat 255. The valve passage 259 at one end 266 thereof, is outwardly bevelled to form an aperture or port opening 267 for cooperation with the pointed end 268 of a needle-valve 270, formed of a thermally-sensitive material such as an aluminum alloy, for a purpose to appear, extending axially into the chamber 250 through a casing guide passage 271. The needle-valve passage 271 is internally threaded as at 275, to provide a threaded seat for an enlarged threaded portion 279 on the needle-valve 270. The threaded portion 279 may be provided by a separate collar suitably secured on the needle-valve 270, or as presently preferred, may be formed as an integral part of the valve. As will appear now, the needle-valve 270 is thus mounted for longitudinal adjustment through its threaded portion 279 in the threaded seat 275, effected upon rotation of the needle-valve element, so as to regulate the position of the port controlling end 268 thereof relative to the port 267 in the valve 258 when the latter is seated to close the main valve port 255.

Packing means 282 arranged in the casing 214 for preventing fluid leakage along the needle-valve, is retained and suitably compressed therein by a gland nut or collar 283 in threaded engagement with the casing. The needle-valve is projected outwardly beyond the collar 283, and

has secured thereto as by set screw 284, a hand control or knob 286 by which the needle-valve may be manually rotated for effecting adjustment thereof. In order to indicate externally of the valve device, the relative position of the valve tip 268 on needle-valve 270, and the port 267 controlled thereby, in any adjusted position of the needle-valve, a pointer 287 may be carried by the knob 286 for cooperation with an appropriate scale (not shown) on the outer end 288 of the casing. Additionally, a readily removable cover or cap 290 may be threaded onto the casing end 288 for protecting the manual control end of the needle-valve.

Fluid communication between the valve chamber 250 at the inner end 262 thereof, and the discharge passage of the pump is effected by the passage 218 laterally in the valve casing 214 in the zone of the cap element 211. On the opposite side of the valve 258 and near the end 251 of chamber 250, is a fluid passage 292 extending from the chamber through a valve casing extension or lateral boss 294, and communicating with this passage is one end of the conduit 42 extending to valve motor 40. Connection of the conduit 42 to the casing extension 294 may be effected by a suitable coupling 295 (Fig. 1). In addition, a relief port 296 is provided in a side wall portion of the valve 258, for a purpose which will appear presently.

Turning now to the operation of the presently described control valve, it will be observed that upon the suction or down stroke of the pump plunger, fluid under the pressure head afforded by the fluid supply source 27, will flow into the pump cylinder and therethrough to the valve chamber 250 through the passage 218. As the engine camshaft through cam 176 thereon, effects upward or delivery displacement of the pump plunger, the fluid ahead of the plunger will be placed under considerable pressure and will react against the valve 258 to displace the same against the bias of valve spring 263, for establishing full fluid discharge through the main port 255. The fluid under pressure thus passing through port 255 and about valve element 258, and thence through conduit 42 to the engine valve motor 40, causes motor operation to open the engine valve.

Upon pressure release by the pump as the pump plunger approaches or attains the end of its delivery stroke, the fluid in conduit 42 will be released for return through valve device 43 and the pump, to the supply header 28. By reason of the restriction or throttling action of the fluid return flow by the valve device 43, as will be presently described, sudden closure of the engine valve is effectively prevented. If such were permitted, a rapid fluctuation or surging of the fluid column between the valve motor and pump, normally would be present, which would tend to produce a fluid hammer effect upon the motor and therethrough, upon the engine valve, tending to or perhaps causing rapid partial opening and closure of the valve, with attendant disadvantages of abnormal wear of the valve parts and a noisy valve operation.

Upon pressure release in the system, the spring 263 of valve assembly 43, displaces valve 258 to port-closing position (Fig. 2) relative to the main port 255. However, when this occurs the return flow of fluid to the pump is established at a greatly reduced or attenuated rate of flow, through the valve passage 259 and the port opening 267. The restriction of fluid return-flow through port 267 as determined and controlled by the adjust-

able needle-valve 270 through regulated projection of its port control tip end 268 in the bevelled port opening 267, thus results in retarding closing-movement of the engine valve to an extent which corresponds relatively closely to the degree of return-flow restriction imposed by the coacting port 267 and needle-valve 270 in any adjusted position of the latter. Although a very small portion of the fluid returned through the pump, normally will be by-passed about the needle-valve controlled port 267 through the small lateral opening 296 in the valve 258, the opening 296 serves principally as a pressure relief expedient, and serves also to dampen oscillations or surges, hence acts to prevent local pressure build-up in the fluid return line from the valve motor 40, in the event the needle-valve 270 is projected inwardly inadvertently or otherwise, to an extent such as to close the throttling port 267 by the valve tip 268. In normal operation, the small leakage at the opening 296 may be readily compensated for by proper adjustment of the needle-valve. The ports 267 and 296, because small in effective area, exhibit a marked effect in damping out line surges, particularly just after closing of the associated engine valve.

As hereinbefore indicated, the needle-valve 270 is formed from a thermally-sensitive material such as a suitable aluminum alloy, whereby to provide for automatic or self-adjustment in the return-flow throttling function of the valve device, attained responsively to and in accordance with temperature differences in the actuating fluid employed in the system. For example, during initial or starting operation of the engine embodying the present valve-actuating system, the valve-actuating fluid may be relatively cool and hence subject to a greater flow-inertia than obtains when the fluid is relatively warm or at a higher temperature. The thermal contraction of needle-valve 270 resulting from and in direct proportion to the low temperature of the actuating fluid, thus affords an increased opening of the return-flow port 267 by the retractive displacement of the needle-valve tip 268 relative to the port-opening 267, whereby to compensate for the greater flow-inertia of the fluid throttled in its return-flow through the valve device. Normally and as a result of continued engine operation, the temperature of the actuating fluid may rise to an appreciable degree, in consequence whereof, the needle-valve element 270 will undergo thermal expansion in proportion to the rise in fluid temperature, to increase thereby and in corresponding degree, the return-flow restriction effected by the needle-valve at the port 267. Accordingly, the needle-valve control is thus manually adjustable for regulating the return-flow throttling function of the valve device 43 in accordance with given conditions of engine operation, and self-adjustable in any control setting of the needle-valve, to compensate for temperature differences of the actuating fluid in the system. The latter as now appears, serves to equalize the throttled return-flow of fluid through the valve device, as changes occur in the temperature of the actuating fluid.

During the throttled return flow of fluid from the valve motor, a certain portion of the fluid normally will be returned through the pump to the supply header 28, under a pressure determined in part, by the pressure exerted on the fluid by the action of the valve motor 40 in closing the engine valve. That portion of the

fluid attaining the header 28 is, however, under sufficient pressure to maintain fluid flow along the header and into the return pipe 32, for return to the fluid source 27.

5 The foregoing indicates the character of hydraulic engine valve actuation attained by the presently described exemplary system and the control function therein of the throttling valve device forming the subject of this invention. The control of valve closure afforded by the device 43 upon pump release of fluid pressure on the engine valve, is of particular advantage in the attainment of smooth, quiet and efficient valve operation. While the improved control valve assembly has been described and illustrated herein in association with a fluid impulse actuating system for engine cylinder valves, the application thereof is not so limited, as the device may be readily employed in fluid pressure systems for actuating or controlling the actuation of mechanism other than valves and the like, and for the damping of unwanted oscillation in hydraulic systems generally.

10 It will be understood, of course, that certain changes or modifications in the several elements of the control valve mechanism and in the arrangement thereof may be effected without departing from the spirit and full intended scope of the invention, as defined by the appended claim.

I claim:

15 In a discharge valve assembly for a high pressure plunger type pump, a structure forming a valve body having an inlet and an outlet, a valve seat in said body providing communication between the inlet and the outlet, a valve coacting with said seat, a spring urging the valve into closing position on said seat, said valve having a passage extending therethrough, and an adjustable throttling element mounted in the inlet of the valve body coacting with said passage when the valve approaches seating position, the valve being so formed as to provide a second passage 20 therein establishing a continuously open path for fluid flow through the valve at all times, where- 25 by to prevent complete obstruction of flow by the throttling element, or otherwise, in any position of the valve.

HENRY SCHRECK.
